United States Patent Office.

WILLIAM C. GOODWIN, OF HAMDEN, CONNECTICUT.

Design No. 4,369, dated September 27, 1870.

DESIGN FOR A MECHANICAL TOY FIGURE.

The Schedule referred to in these Letters Patent and making part of the same.

To all whom it may concern:

Be it known that I, WILLIAM C. GOODWIN, of Hamden, in the county of New Haven and State of Connecticut, have invented a new Design for Figure of Mechanical Toy; and I do hereby declare the following, when taken in connection with the accompanying drawing and the letters of reference marked thereon, to be a full, clear, and exact description of the same, and which said drawing constitutes part of this specification, and represents a front view.

This invention relates to a design for toys, such as are applied to heating apparatus to receive a power to operate them from the rising heat.

The design represents the figure of Cupid forging a spear. The hammer held in the right hand is, by the operation of the shaft A, caused to rise and fall, apparently striking a blow, as denoted in broken lines.

I claim as my invention—

The design for figure for mechanical toys, as described and shown.

W. C. GOODWIN.
